UNITED STATES PATENT OFFICE.

HERMAN BESSER AND JESSE H. BESSER, OF ALPENA, MICHIGAN.

CEMENT-BLOCK MACHINE.

Application filed August 4, 1923. Serial No. 655,648.

To all whom it may concern:

Be it known that we, HERMAN BESSER and JESSE H. BESSER, residents of the city of Alpena, in the county of Alpena and

5 State of Michigan, and citizens of the United States, have invented certain new and useful Improvements in Cement-Block Machines, of which the following is a specification.

10 Our invention relates to cement block machines and more especially to the class in which removable cores and plates are actuated toward and from the mold, certain of these plates being used both at the ends 15 of the mold and, when it is desired to divide the same into a plurality of blocks, at an intermediate point, the plates being removable with certain of the cores.

It is an object of our invention to operate 20 the various cores and plates by a single hand lever which heretofore has necessitated the removal of all parts at one time thus requiring great strength and labor in actuation, as well as tending to injure the product in the 25 mold. In overcoming these disadvantages, it is our purpose to operate these devices by the usual single lever but, by the provision of certain connecting elements, start the withdrawal of the various core and plate 30 units automatically at predetermined intervals, so that a part only of said units are started in said withdrawal at one time.

It is a further object of our machine to 35 actuate the core plungers by means of a common transverse bar having apertures or slots of different sizes for receiving therein the ends of pins fixed to the plungers, so that, as the bar moves, these pins and with them the cores and plates will be actuated at different intervals.

40 We attain these and other objects of our invention by the construction hereinafter claimed and described, and illustrated in the drawings in which—

45 Figure 1 is a plan view of our invention, showing the cores and plungers in their advanced position, and with the top plate removed;

Figure 2 is a view similar to Fig. 1, but 50 with the cores withdrawn;

Figure 3 is a side elevation of the machine;

Figure 4 is a longitudinal section as 55 shown along the line 4—4 of Fig. 1, and

Figure 5 is a perspective view of a double block formed by our machine.

Referring to the structure in detail, similar reference characters designating like parts throughout the specification and drawings, 10 represents the frame in general, the 60 same being of quite usual construction, suitable side, end, and cross pieces being used to support the mold walls and actuating means for the cores and dividing plates, 11 65 designates a swinging plate, usually metal, pivoted to the frame at 12, and held vertical during the block formation, but providing for swinging downward to horizontal position as shown in dotted lines in Fig. 3 when the blocks are to be released. Upon 70 the bench plate 13 is supported up-standing posts 14 bearing above them the cross plate 15 which serves as the base for the mold cavity.

Upon the outer edge of 15 is removably 75 supported the pallet 16 which in turn is supported in position at the back by the plate 11. Since the parts 11 and 13 to 16 may swing together on a common pivot 12, it is 80 evident that in the lowered position, as shown in Fig. 3, the formed blocks will 85 rest upon the pallet which may be removed manually carrying the blocks with it. The rear plate of the mold cavity is represented by the part 17 which is fixed to the frame at either side of the machine, and is apertured 90 to receive there-through the cores 18 and plates 19. It will be noted that the end plates 19 are secured to half cores 20 while the intermediate plate 19^a is usually formed 95 integral with the central core 21, so that by this construction two blocks may be formed by the use of three plates, two half cores and three full size cores. Of course, the machine may be expanded to produce a larger 100 number of blocks at the same time by the use of more dividing plates; and the number of hollow spaces within each block increased by multiplying the number of cores used.

These cores and plates are quite securely 100 attached to the ends of plungers 22 which extend rearwardly for connection with a common actuating mechanism. As the plungers are withdrawn, the cores are pulled back through the apertures 24 of the plate 17, so that the molded blocks are ready for 105 removal. It will be apparent that quite strong force is required to start withdrawal of a plurality of cores and plates—especially of five or more cores and three plates, as 110 are illustrated in this case. This is due to the molding of the plastic material about

the cores by tamping during the forming of the blocks, so that the removal of the cores tends to break down the molded form of the material in the attempt of the latter to follow the cores in their withdrawal because of the effect of atmospheric pressure.

To means for obviating this condition are provided namely: The cores 18 are made hollow but have one closed end 23 to which the plungers 22 may be secured, and said closure 23 is apertured at 25 to provide for entrance of air to fill the vacuum otherwise caused by withdrawal of the core; then, means are provided for withdrawing the cores at different times with intervals between successive actuations, though such intermittent actuation is caused by a common source of energy, as will be later explained. The end half-cores 20 are also hollow and provided with the vent opening 25 as well as the others, and are integral with the end plates 19, but are otherwise like the cores 18. The central core 21 is integral with the plate 19^a which is divided and secured above and below to the core as fins, in the manner illustrated in the drawings.

For actuating the cores, the following mechanism is provided: A bell-crank lever 26 pivoted to the frame part 13 at 27, the latter being a transverse rock shaft to which is keyed the said lever at one end, and an actuating arm 28 at the other. Upon the upper side of the frame 10 above the plungers is shown a transverse bar 29 suitably guided for movement in a direction longitudinal of the plungers 22. This bar has a series of apertures 30, 31 and 32 which receive loosely therethrough pins 33 carried by the plungers, so that movement of the bar actuates the various plungers and cores, but at different times. The arm 34 of the lever and the arm 28 are operatively connected respectively to the ends of the said bar 29, by links 35 so that force applied to the lever 26 will slide the plungers 22 in their guides and thereby actuate the cores in withdrawal from the chamber as well as in inserting them when preparing for a new molding operation. It is noted in this connection, that the pins 33 are smaller than apertures 31 and 32, and that 31 is smaller than 32, so that beginning the actuation of the lever 26 from the position of the parts as shown in Fig. 1, the aperture 30 will move the parts 21 and 19^a first, and the cores 18 and 20 will receive no impulse until core 21 has moved some little distance depending on the difference between the size of apertures 30, 31 and 32. After bar 29 has moved a short distance, cores 18 will begin rearward movement, and later cores 20 and plates 19 will follow in order. When all the cores and plates have been withdrawn, they will take the relative position shown in Fig. 2. As the lever is moved to push the cores for-

ward, for another molding operation the same relative movement of the plungers will occur but in the reverse direction. At the close of this movement, the forward ends of all the cores and plates will be in alinement and substantially in contact with the pallet 16 as shown in Fig. 1.

It will be obvious that when once the core is started in its rearward movement, there is much less difficulty in continuing the withdrawal from the pasty mass of material in which they are imbedded; so that if once the rearward movement of the cores can be well established, little difficulty is experienced in fully withdrawing them. For this reason, it is only necessary to provide the apertures referred to as illustrated, so that it will not be required to start all the plungers and cores at one time. It has been found by actual experiment, that the interval between the successive impulses exerted on the different plungers may not be very large to attain the result desired. If, however, a greater difference in the time of starting should be found essential or expedient, the said apertures, shown in these views as circles should be changed to elongated slots extending in the direction of the length of the plungers, so that a greater difference in time interval would be attained.

While the slotted transverse bar and pin structure has been shown, and has been found exceedingly practical in use, many modifications of such arrangement will occur to one skilled in the art, now that the general idea of the actuation is disclosed. For example, the bar 29 may itself carry vertical pins, and the plungers provided with side blocks attached thereto against which the pins would bear as the bar is moved rearwardly. It will also at once be obvious that the reverse arrangement of slots and pins shown in Figs. 1 and 2 may be used, the pins being carried by the bar, and the slots or apertures being drilled through the plungers. It will be readily understood that these and other changes in the relative arrangement and construction of the various parts of our improved block machine can be made and substituted for those herein shown and described, without departing from the spirit of our invention, the scope of which is set forth in the appended claims.

We claim:

1. A cement block machine having a mold chamber, cores movable into and out from said chamber, a supporting frame, a swinging member pivoted to said frame, and means connected with said member whereby continuous movement of said member in either direction will actuate the several cores in a predetermined succession.

2. A cement block machine having a mold chamber the rear wall of said chamber hav-

ing a plurality of aligned openings, cores fitting said openings and movable therethrough into and out of said chamber, said cores being hollow and having one closed 5 end provided with a vent aperture, a supporting frame, a swinging member pivoted to said frame and means connected with said member for actuating the several cores in a predetermined succession.

10 3. A cement block machine having a mold chamber and cores movable into and out of said chamber, said cores being hollow and having one closed end, said end having a vent aperture through the closure, a supporting frame, slideable plungers guided in said frame and fixed at one end to the closed ends of the cores, a bell-crank lever pivoted on the side of said frame and means connected with one arm of said lever for actuating 15 the several plungers and thereby the cores in a predetermined succession.

4. In a cement block machine having a mold chamber, the combination of a series of cores movable into and out of said chamber 20 in lateral alignment, slideable plungers each fixed to a core, means for guiding the plungers in their longitudinal movement, protuberances on said plungers for actuating them, a supporting frame, a transverse rock 25 shaft pivoted in said frame, a lever keyed to said shaft, for rocking the latter, and means connected with said shaft and contacting said protuberances for actuating the several cores in predetermined succession.

25 5. In a cement block machine having a mold chamber and cores movable into and from said chamber, the combination with slideable plungers each fixed to a corresponding core, and means for guiding the bars and 30 thereby the cores in the same direction as the latter, a frame for supporting the said chamber, cores and plungers, a lever pivoted on the side of said frame, means connecting one end of said lever to said transverse bar for 35 actuating the latter, and means connecting the plungers with said transverse bar whereby the several plungers will be moved in a predetermined succession.

6. In a cement block machine having a 40 mold chamber, the combination of a series of cores movable into and out from said chamber in lateral alignment, vertical plates integral with the end cores, a dividing plate fixed to one of the intermediate cores, slideable plungers each fixed to a core and guided for longitudinal movement, a supporting frame, a transverse bar adjacent the plungers and slideable toward and from said

chamber a lever pivoted on the side of said frame, means connecting the plungers with said transverse bar whereby the continuous operation of the lever in either direction will first actuate the core and dividing plate, after an appreciable interval will start the operation of the intermediate cores and last 65 of all the end cores and plates and thereafter continue the movement of all the cores and plates together as a unit.

7. In a cement block machine having a mold chamber and cores movable into and from said chamber, the combination with slideable plungers each fixed to a corresponding core and means for guiding the plungers in their longitudinal movement, of a transverse bar adjacent the plungers and movable 70 in the same direction as the latter, and having a plurality of apertures therethrough of different size, there being an aperture adjacent each plunger, a frame for supporting said chamber, cores and plungers, and a lever pivoted on the side of said frame, means connecting one end of said lever to said transverse bar for actuating the latter, and means fixed to the plungers and extending 75 loosely through the said apertures in the transverse bar whereby movement of the lever will operate the several plungers and thereby the cores in predetermined succession.

8. In a cement block machine having a mold chamber and cores movable into and from said chamber, the combination with slideable plungers each fixed to a corresponding core and means for guiding the plungers in their longitudinal movement, of a transverse bar adjacent the plungers and movable 80 in the same direction as the latter, and having a plurality of apertures therethrough of different size, there being an aperture adjacent each plunger, a frame for supporting said chamber, cores and plungers, and a lever pivoted on the side of said frame, means connecting one end of said lever to said transverse bar for actuating the latter, and means fixed to the plungers and extending 85 loosely through the said apertures in the transverse bar whereby movement of the lever will operate the several plungers and thereby the cores in predetermined succession.

9. In a cement block machine having a mold chamber and cores movable into and from said chamber, the combination with slideable plungers each fixed to a corresponding core and means for guiding the plungers in their longitudinal movement, of a transverse bar adjacent the plungers and movable 90 in the same direction as the latter, and having a plurality of apertures therethrough of different size, there being an aperture adjacent each plunger, a frame for supporting said chamber, cores and plungers, and a transverse rock shaft pivoted in said frame, an arm keyed to said shaft at one end and a lever at the other, links connecting one end of said lever and the arm to the ends of said transverse bar for actuating the latter, and pins secured to the plungers and extending 95 loosely through the said apertures in the transverse bar whereby movement of the lever will operate the several plungers and thereby the cores in predetermined succession.

10. In testimony whereof we hereunto affix our signatures.

HERMAN BESSER.
JESSE H. BESSER.
